UNITED STATES PATENT OFFICE

2,632,438

TOP PILOT COVER PLATE

John E. Chambers, Shelbyville, Ind., assignor to
Chambers Corporation, a corporation of Indiana

Application December 10, 1948, Serial No. 64,545

4 Claims. (CL 126—214)

1

This invention relates to a top pilot cover plate, and has particular reference to means for locating the various top burner grates relative to the top burners.

It has been customary to position the grates for top burners in gas stoves so that the grate fingers will be aligned with the spaces between the individual burner elements of the burners. This arrangement adds to the life of the grates because the grate fingers are not directly over the flame. The positioning of the grate fingers between the individual sources of flame also provides maximum heating efficiency for the cooking vessel on top of the grate because the flames are not intercepted by the grate fingers.

The grates have heretofore been placed in predetermined position relative to the burners by providing either a notch or a projection on each grate, and an interengaging projection or notch on the stove top adjacent the burner opening. This arrangement is comparatively expensive because of the multiplicity of notches and projections required.

In accordance with the present invention I provide a top pilot cover plate with notches on its outer edge that are adapted to receive the outer extremities of the long fingers of the top burner grates surrounding the top pilot cover plate. The grates are properly located without any special projection or notch being required on any of the grates and without the necessity of providing a notch or projection on the stove top adjacent each grate.

Another advantage of the present structure is the capability of the top pilot cover plate to support a cooking vessel at the same level as the top burner grates so that there is very little danger of spilling the contents of a cooking vessel in moving it from any top burner grate to the top pilot cover plate or from the top pilot cover plate to any top burner grate.

The structure by which the above advantages are attained will be described in the following specification, taken in conjunction with the accompanying drawings, in which:

Figure 1 is a fragmentary detail perspective showing one of the grate fingers and the top pilot cover plate having a notch to receive the end of the grate finger;

Fig. 2 is a top plan view of the stove top showing four top burner grates surrounding the top pilot cover plate, with one finger from each grate interengaged with a notch in the top pilot cover plate;

Fig. 3 is a fragmentary detail perspective view

2

showing the underside of the top pilot cover plate, with the pilot shield removed, and a portion of the stove top in which the top pilot cover plate is adapted to be positioned;

5 Fig. 4 is a cross sectional view, taken along the line 4—4 of Fig. 2, showing the relationship between the pilot light, the pilot light cover plate, and the adjacent burners and grates;

Fig. 5 is a top plan view showing a modified 10 form of top pilot cover plate positioned in the stove top;

Fig. 6 is a fragmentary cross sectional view, 15 taken along the line 6—6 of Fig. 5, showing the top pilot plate spaced above the opening in the stove top in solid lines, and in the opening in dotted lines; and

Fig. 7 is a top plan view of the opening in the stove top, showing in dotted lines the radial spokes of the top pilot plate as positioned in the opening.

20 In the drawings, the reference numeral 2 indicates the top of a stove having a plurality of top burners 3 arranged around a pilot light 4. The pilot light is connected to each of the top burners by a flash tube 5. The top burners may be of any shape or style, but are shown as having four individual chimney burners 6. A top grade 7 is positioned over each burner 3.

Each grate comprises an annular member 8 and a plurality of alternate long and short grate fingers 9 and 10 integral therewith, or secured thereto in any suitable manner. The annular member seats on a ledge 11 extending inwardly around each burner opening 12. As shown in Fig. 2, grate fingers 9 are positioned between individual chimney burners 6 to protect them from direct contact with the flames from the burners, and to provide maximum heating efficiency for each burner by not deflecting the flame. The means for facilitating this alignment of the grate fingers with the individual chimney burners, and for preventing accidental rotational displacement of the grates comprises the essential feature of the present invention.

45 The stove top 2 has an opening 13 over pilot light 4 which is spaced equidistant from openings 12. In the embodiment of the invention shown in Figs. 1 to 4, inclusive, opening 13 is circular in shape. The top pilot cover plate 14 is substantially square, with each side slightly concave, but may be of any desired shape so long as any grate finger 9 will extend slightly past the periphery of the cover plate when the grate is properly positioned. Each side of the cover plate is provided with a notch 15, positioned substantially

centrally of the side, adapted to receive the end of a grate finger 9 from each grate. The concave sides of the top pilot cover plate facilitate the entry of the grate fingers in the notches.

A locating pin 16 projecting downwardly from the underside of cover plate 14 fits into a locating hole 17 to properly position the cover plate and to prevent it from rotating. It will be obvious that pin 16 and hole 17 may be reversed, or any other suitable means may be used to locate cover plate 14 or to keep it from rotating relative to the stove top.

Cover plate 14 is preferably provided with openings 18 so that the pilot light may be used to keep a pot or dish warm. The openings 18 also prevent the top of the stove from getting overheated by the constantly burning pilot light because they permit the heat from the pilot light to escape to the atmosphere. Radial spokes 19 fitting into stove top opening 13 hold the cover plate therein. A shield 20 secured to cover plate 14 serves to protect the pilot light from drafts and from liquids that may be spilled on the top of the stove.

As shown in Fig. 4, the top of cover plate 14 lies flush with the tops of grates 7 so that a cooking vessel may be pushed from any grate across the cover plate and to any other grate without any appreciable danger of spilling its contents.

In the embodiment of the invention shown in Figs. 5, 6 and 7, the stove top is provided with a square opening 21. The top pilot cover plate 22 is substantially the same as cover plate 14 but no locating pin and hole are necessary because radial spokes 19 fit in the corners of opening 21 and are prevented from rotating by the square shape of the opening. As in the embodiment previously described, each side of cover plate 22 is notched, as indicated at 15, to engage the ends of grate fingers 9.

Although the illustrated form of burner described above is of the type having four individual chimneys, it will be obvious that the advantages of the invention herein described may be utilized with other types of burners.

Although I have described two preferred embodiments of my invention in considerable detail, the description thereof is intended to be illustrative, rather than restrictive, as many details may be modified or changed, without departing from the spirit or scope of my invention. Thus, for example, stove top opening 21 may have any non-circular shape and the shape and arrangement of the radial spokes 19 may be such as to interengage with the sides of the opening and thereby prevent the cover plate from rotating. Accordingly, I do not desire to be restricted to the exact structure described.

I claim:

1. In combination with a stove top having a plurality of apertures therein, a top pilot cover plate positioned in one of said apertures, interengaging means on said stove top and said top

pilot cover plate to prevent rotational movement of said top pilot cover plate, a plurality of notches in the edges of said top pilot cover plate, and a grate positioned in each of the other of said apertures, each of said grates having a plurality of grate fingers extending horizontally beyond the diameter of the aperture in which its grate is positioned, the ends of said grate fingers being individually engageable with one of said notches to prevent rotational movement of said grate.

2. In combination with a stove top having a plurality of apertures therein, a top pilot cover plate positioned in one of said apertures with its marginal edge portions overlying said stove top adjacent the aperture in which said top pilot cover plate is positioned, an opening in the portion of said stove top which said top pilot cover plate overlies, a projection rigidly secured to the underside of said top pilot cover plate, said projection fitting in said opening in said stove top to secure said top pilot cover plate against rotational movement, a plurality of notches in the marginal edge of said top cover pilot plate, and a plurality of grates positioned in the other apertures in said stove top, each of said grates having a grate finger engageable with one of said notches to prevent rotational movement of said grates.

3. In combination with a stove top having a non-circular opening, a top pilot cover plate having a depending portion fitting into said opening and held against rotation, a plurality of notches in the outside edge of said cover plate, and a plurality of grates each having grate fingers individually engageable with said notches to hold said grates against rotational displacement.

4. In combination with a stove top having a plurality of openings each receiving a top burner grate, another opening positioned equidistant from said first mentioned openings, a top pilot cover plate having a depending portion fitting into said second mentioned aperture and held against rotation, a plurality of notches in the peripheral edge of said cover plate, and a plurality of grate fingers on each of said grates, said fingers being individually engageable with said notches to hold said grates against rotational displacement.

JOHN E. CHAMBERS.
